DRAFT AND BUFFER GEAR

Stacy E. Haseltine, Glen Ellyn, Ill., assignor to
W. H. Miner, Inc., Chicago, Ill., a corporation
of Delaware

Application March 23, 1936, Serial No. 70,289

12 Claims. (Cl. 213—9)

This invention relates to improvements in draft and buffer gears especially adapted for mine cars.

One object of the invention is to provide a combined draft and buffer gear for mine cars, where-
5 in both the draft and buffering forces are cushioned by the same shock absorbing means, which is directly actuated by the buffering head of the car, and wherein simple and efficient mechanism is provided for transmitting the draft or pulling
10 forces from the car coupling means to the buffering head.

A more specific object of the invention is to provide in a mechanism of the character set forth in the preceding paragraph shock absorb-
15 ing means at opposite sides of the buffering head yieldingly opposing inward movement of said head, and simple and efficient lever means ar-
ranged to transmit the draft forces directly to the buffering head in such a manner that the forces
20 acting on the buffering head are transmitted to opposite sides of the head to produce a balanced action and effect inward movement of the head.

Other objects of the invention will more clearly appear from the description and claims herein-
25 after following.

In the drawings forming a part of this specification, Figure 1 is a horizontal sectional view through the end portion of a mine car, corresponding substantially to the line 1—1 of Figure
30 2 and showing my improvements in connection therewith. Figure 2 is a vertical sectional view, corresponding substantially to the line 2—2 of Figure 1. Figure 3 is a vertical sectional view, corresponding substantially to the line 3—3 of Figure 2. Figure 4 is a view, similar to Figure 1, illustrating another embodiment of the invention. Figure 5 is a vertical sectional view, corresponding substantially to the line 5—5 of Figure 4. Figures 6 and 7 are vertical sectional views, corresponding respectively to the lines 6—6 and 7—7 of Figure 5. Figure 8 is a view, similar to Figure 1, illustrating still another embodiment of the invention. Figure 9 is a vertical sectional view, corresponding substantially to the line 9—9 of Figure 8. Figure 10 is a vertical sectional view, corresponding substantially to the line 10—10 of Figure 9.

Referring first to the embodiment of the invention illustrated in Figures 1, 2, and 3, 10 indi-
50 cates the vertical wall at one end of a mine car, 11 the floor, and 12 an angle bar member connecting the end wall 10 and the floor 11 and forming, in effect, the end sill member of the car.

My improved combined draft and buffer gear,
55 as shown in Figures 1, 2, and 3, comprises broadly

a support A; a buffer head B; draft lever mem-
bers C and D; a coupling pin E for connecting
the levers C and D to the usual coupling link;
and spring resistance elements F—F.

The support A is in the form of a housing fixed 5 to the vertical end wall 10 of the car. The sup-
port A includes a vertical platelike portion 13 riveted to said end wall 10. The platelike portion 13 forms the back wall of the housing and is provided with outwardly projecting flanges 10 forming spaced vertical side walls 14—14 and spaced horizontally disposed top and bottom walls 15—15 of said housing. The bottom wall 15 is centrally cut away, as indicated at 16, and the top wall 15 is vertically offset at the central por- 15 tion, as indicated at 17. The portion 17 of the top wall 15 is heavier than the side portions of said wall and projects outwardly beyond said side portions, as clearly shown in Figures 1 and 3. The section 17 of the top wall is connected to 20 the side portions of said top wall by short vertical flanges 18—18. Substantially midway be-
tween the top and bottom thereof, the platelike portion 13 is provided with an outstanding, central, horizontally disposed lug 19. The lug 19 and 25 the flange portion 17 are provided with vertically aligned, elongated coupling pin-receiving open-
ings 20—20 adapted to accommodate the usual coupling pin E.

The buffer head B is open at the rear and com-
prises a vertical front wall 21, spaced, horizon-
tally disposed, top and bottom walls 22—22, and spaced, vertical, side walls 23—23. The front wall 21 presents a transversely curved outer buffering face adapted to cooperate with the buffering 30 head of an adjacent car. At the rear ends, the top and bottom walls 22—22 of the buffer head B are provided with narrow, vertically disposed, inturned flanges 24—24, for a purpose herein-
after pointed out. The buffer head B is telescoped 35 within the housinglike support A, being slidable between the top, bottom, and side walls 15—15 and 14—14 of said support. Substantially mid-
way between the opposite sides of the buffering head B, the rear portions of the top and bottom walls 40 22—22 are cut away, as indicated at 25—25, to provide clearance for certain parts of the mecha-
nism. The central portion of the top wall 22 of the buffer head B is depressed, or downwardly offset, as indicated at 26, to provide a guide sur- 45 face or support for the coupling link, which is indicated by 27.

The lever members C and D are of similar design, except as hereinafter pointed out. Each of these lever members comprises a vertical, 50

sleevelike bearing portion 28 having a pair of vertically spaced, horizontally disposed, laterally projecting arms 29-29 at the lower end portion thereof. The lever member C has a laterally projecting arm 30 in substantial alignment with the top arm 29 thereof and projecting diametrically opposite thereto from the bearing sleeve 28. The lever member D has a horizontal arm 31 at the upper end of the sleeve 28 thereof, projecting in a direction diametrically opposite to the arms 29-29 of said lever member. As shown most clearly in Figures 1 and 2, the lever members C and D are arranged at opposite sides of the mechanism, each lever being pivotally supported 10 on a vertically disposed pivot pin 32, extending through the sleeve 28 thereof, and aligned openings in the bottom wall 15 and the top wall section 17 of the support A. The arms 29-29 of each lever member are so spaced vertically as to engage respectively with the upper and lower flanges 24-24 at the corresponding side of the buffer head B. The outer ends of these arms are 15 preferably rounded off, as shown in Figure 1. The laterally, inwardly projecting arm 30 of the lever member C is disposed immediately above the lug 19 of the housing A, as clearly shown in Figure 2, and is slidable on said lug. The upper side of the arm 30 is preferably in horizontal alignment with the top of the depressed portion 26 of the top wall of the buffer head, said arm and the depressed portion 26 of the top wall of the buffer head forming supporting means for the coupling link 27. The arms 30 and 31 of the lever members C and D are provided with coupling pin-receiving openings 33-33 which are 20 in vertical alignment, when the parts are in the position shown in Figures 1 and 2, to receive the coupling pin E. These openings 33-33 are preferably laterally enlarged to compensate for 25 swinging movement of the lever arms 30 and 31 about the pivots 32-32.

The spring resistance elements F-F are disposed at opposite sides of the mechanism. Each spring resistance element F preferably comprises 30 two coil springs interposed between the front wall 21 of the buffer head B and the opposed seat member 34 on the corresponding side of the platelike portion or back wall 13 of the support or housing A. The coils of the springs are 35 preferably held centered by the usual centering bosses provided respectively on the front wall 21 of the buffer head B and the seat of the support A.

The coupling pin E is engaged through the coupling link 27 and the openings 33-33 at the 40 outer ends of the arms 30 and 31 of the lever members C and D and works in the openings 26-26 of the lug 19 and the wall portion 17 of the housing or support A.

In the operation of my improved draft and 45 buffer gear, the buffing shocks are transmitted from the buffer head of an adjacent car to the buffer head B and the latter is forced inwardly toward the end of the car, thereby compressing the springs F-F against the rear wall of the housing A. The springs F-F thus absorb the 50 buffing shocks.

In a draft action, the coupling link 27 is pulled outwardly thereby, through the connecting pin E, swinging the arms 30 and 31 of the lever members C and D outwardly. The lever arms 29-29 and 29-29 of the lever members C and D are thus 55 swung inwardly. Inasmuch as these arms 29-29 and 29-29 engage the flanges 24-24 and 24-24 of the buffer head B, the latter is forced to move 60 inwardly against the resistance of the springs 65

E-E and the draft shocks are thus cushioned by these springs. Inward movement of the buffer head B is limited by engagement with the seats 34-34 on the rear wall 13 of the housing A, thereby limiting the movements of the lever members C and D in draft. In this connection it is pointed out that outward movement of the buffing head B is limited by the lever members C and D through the arms 29-29 thereof, outward swinging movement of these arms being limited by engagement of the arms 30 and 31 with the back wall 13 of the housing A, each arm 30 and 31 being provided with an extension or lug 35 for this purpose.

Referring next to the embodiment of the invention illustrated in Figures 4, 5, 6, and 7, my improved draft and buffer gear comprises a supporting housing G; a buffer head H; a pair of lever members J-J; a draft member K; and two sets of springs M-M.

The support or housing G includes a vertical back wall 35, spaced side walls 36-36, and top and bottom walls 37 and 38. The back wall 35 is in the form of a platelike member and the walls 36-36, 37, and 38 are in the form of outwardly projecting flanges on said plate. The housing G is secured to the end of the car in the same manner as the housing A hereinbefore described, the platelike member 35 being riveted to the end wall 19 of the car. The bottom wall 38 is downwardly offset at opposite sides of the central portion of said support or housing G to provide pockets 39-39 for certain lever arms, hereinafter more fully described. The central section of the top wall 37 is upwardly offset, as most clearly shown in Figure 5, thereby providing a central pocket 40 and two pairs of pockets 41-41 and 42-42 below the pocket 40, the pockets 41-41 being located at opposite sides of the pocket 40 immediately below the same, and the pockets 42-42 being located at opposite sides of and below the pockets 41-41. The pockets 42-42 are in vertical alignment with the outer side portions of the corresponding pockets 39-39.

The buffer head H is in the form of a transversely arranged buffering member telescoped within the housing G and having outwardly projecting, hollow, laterally spaced, buffer caplike portions 43-43 at opposite sides of the car, said cap portions 43-43 being connected by a beam-like portion 44 integral with said caplike portions. The caplike portions 43-43, together with the connecting beam 44 thus form a single, rigid buffer head structure.

The lever members J-J are of identical design, but reversely arranged. Each lever member comprises a vertically disposed bearing sleeve 45, a laterally, inwardly projecting arm 46 at the upper end of said sleeve, and vertically spaced, laterally, outwardly projecting arms 47-47 on said sleeve embracing the corresponding cap member 43 and respectively engaging top and bottom ribs or lugs 48-48 on said corresponding cap portion 43 of the buffer head H. The lever members J-J are disposed at opposite sides of the center of the mechanism and are swingingly supported on pivot pins 49-49 extending through the sleeve 45-45 of said lever members and the top and bottom walls of the housing G. The lever arms 47-47 of each member J are accommodated for swinging movement in the top and bottom pockets 42 and 39 at the corresponding side of the housing G. The laterally, inwardly projecting top arms 46-46 of the lever members J-J are swingingly accommodated in the pockets 75

41—41 and cooperate with the draft member K.

The draft member K is in the form of a yoke having top and bottom, forwardly projecting, vertically spaced arms 50—50 connected at their rear ends by a relatively heavy vertical section 51. The yoke K is accommodated in the pocket 40 of the housing G and is slidably supported on the beamlike portion 44 of the buffer head H. The arms 50—50 of the draft member or yoke K straddle the extremities of the arms 46—46 of the lever members J—J, and the vertical section 51 of said yoke is provided with rounded bearing seats 52—52 within which the outer ends of the arms 46—46 engage, the extremities of said arms being rounded as shown.

Each set of springs M preferably comprises two coils. The sets are disposed at opposite sides of the mechanism, one set being contained within each buffer cap member 43. The springs of each set are interposed between the vertical rear wall 35 of the housing G and the front wall of the corresponding cap member, and said sets of springs together yieldingly oppose inward movement of the buffer head H.

25 The draft member K is connected to the usual coupling link 53 by a coupling pin 54 engaged through said link and aligned openings in the top and bottom arms 50—50 of the draft member, the link being accommodated between said arms.

In the operation of my improved mechanism, the buffer head H is forced inwardly against the resistance of the springs M—M by engagement with a buffer head of an adjacent car, thus 35 absorbing the buffing shocks. During draft action of the mechanism, the draft member or yoke K is pulled outwardly by the connecting link 53, thereby swinging the arms 46—46 of the lever members J—J outwardly and rocking the lever members on their pivots. The arms 47—47 and 40 47—47 of the lever members J—J are thus swung inwardly forcing the buffer head H inwardly also by engagement with the lugs 48—48 of the cap members 43—43 of said head. The draft shocks 45 are thus absorbed by the springs M—M which yieldingly oppose inward movement of the buffer head H.

Referring next to the embodiment of the invention illustrated in Figures 8, 9, and 10, my improved draft and buffer gear comprises a supporting housing P; a buffer head R; a pair of levers S—S; a draft member T; and spring resistance means W.

The housing P is similar to the housing G, hereinbefore described, and is fixed to the vertical end wall 10 of the car in a like manner. The lever members S—S and the draft member T are also of substantially the same design as the levers J—J and the draft member K, hereinbefore described.

60 The buffer head R is in the form of a hollow cap open at the rear and having a transversely rounded, outer buffer face. The head R comprises spaced, horizontally disposed top and bottom walls 60—60, spaced, vertical side walls 61—61, and a vertical front wall 62. The head R is telescoped within the housing G and is slidable thereon. At opposite sides of the head R, top and bottom abutment ribs or lugs 63—63 and 65 63—63 are provided, which are engaged by the arms 64—64 and 64—64 of the lever members S—S. The lever members S—S are rocked by the draft member T in a manner similar to that described in connection with Figures 4, 5, 6, and 7, 75 the draft member cooperating with the inwardly

extending arms 65—65 at the upper ends of said lever members S—S.

The spring W is disposed within the buffer head R and comprises four coil springs, two of said coil springs being arranged at the center 5 of the mechanism between the pivots of the lever members S—S, and the remaining coil springs being arranged at opposite sides of the mechanism outwardly of said pivots. The coils forming the spring means M are interposed between 10 the front wall of the buffer head and the vertical rear wall of the housing, thus yieldingly opposing inward movement of said head.

The operation of the device shown in Figures 8, 9, and 10 is substantially the same as the operation of the device shown in Figures 4, 5, 6, and 7, and therefore needs no further description.

I have herein shown and described what I now consider the preferred manner of carrying out my invention, but the same is merely illustrative and 20 I contemplate all changes and modifications that come within the scope of the claims appended hereto.

I claim:—

1. In a combined draft and buffer gear for cars, 25 the combination with a transversely disposed buffer head at the end of the car; of cushioning means opposing inward movement of said head; a pulling element actuated in draft; and lever means actuated by said pulling element and engaging said buffer head at opposite sides to force the same inwardly in draft.

2. In a combined draft and buffer gear for cars, the combination with a fixed abutment means on the end of the car; of a supporting 35 member; a pulling member; a transversely disposed buffer head having portions at opposite sides of said pulling member, said buffer head being slideable inwardly on said supporting member; cushioning means interposed between said 40 buffer head and said abutment means and opposing inward movement of said head; and lever means at opposite sides of said pulling member for transferring the draft force from the pulling member to opposite sides of said buffer head for 45 forcing the latter inwardly toward said fixed abutment means.

3. In a combined draft and buffer gear for cars, the combination with a fixed abutment means on the end of the car; of a supporting 50 member; a transversely disposed buffer head at the end of the car movable inwardly on the supporting member; bearing abutments on said head at opposite sides thereof; cushioning means interposed between said abutment means and head 55 opposing inward movement of said head; a pulling member movable outwardly away from the end of the car, said pulling member being disposed between said bearing abutments; and lever means at opposite sides of said pulling member, each lever means having arms respectively operatively engaging one of said bearing abutments and said pulling element to force said head inwardly when said lever means is swung by outward movement of said pulling member.

4. In a combined draft and buffer gear for cars, the combination with fixed abutment means on the end of the car; of a supporting member; a transversely disposed buffer head movable inwardly on the supporting member; cushioning 70 means interposed between said head and abutment means opposing inward movement of the buffer head; a pulling member movable outwardly away from the end of the car in draft; and a pair of levers, each of said levers being pivoted 75

between its ends, the pivots of said levers being disposed respectively at opposite sides of the pulling member, and each lever having one end engaging the pulling member and the other end 5 engaging the buffer head for forcing the latter inwardly when the pulling member is moved outwardly away from the end of the car.

5. In a combined draft and buffer gear for cars, the combination with fixed abutment means 10 on the end of the car; of a supporting member; a transversely disposed, horizontally arranged buffer head movable inwardly of said supporting member; cushioning means interposed between said head and said abutment means, said cushioning means opposing inward movement of the buffer head; transversely arranged abutments on 15 said head at opposite sides thereof; a pulling member movable outwardly away from the car in draft, said pulling member being movably mounted at a point between said transverse abutments; and a pair of levers at opposite sides of said pulling member, each lever being pivoted between its ends for swinging movement about a vertical axis, each lever having its opposite ends in 20 operative engagement respectively with the pulling member and the transverse abutment at the corresponding side of the buffer head.

6. In a combined draft and buffer gear for cars, the combination with a support; of a pulling 30 member movable outwardly away from the end of the car; levers at opposite sides of said pulling member pivoted on said support, each lever having laterally, inwardly and outwardly extending arms, said inwardly extending arms 35 being operatively engaged by said pulling member to swing said arms outwardly in draft to rock said levers and swing the outer arms inwardly; a transversely disposed buffer head having abutment means thereon at opposite sides thereof engageable by said outer arms to move said buffer head; and cushioning means opposing inward movement of said head.

7. In a combined draft and buffer gear for cars, the combination with a support; of a transversely 45 disposed buffer head movable inwardly on said support; cushioning means opposing inward movement of said head; top and bottom abutments on said buffer head at each side thereof; a pulling member; and a pair of lever members 50 pivoted on said support at opposite sides of said pulling member, each of said lever members having a laterally, inwardly extending arm and a pair of laterally, outwardly extending arms, said inwardly extending arm of said lever being engaged with and actuated by said pulling member 55 and said outwardly extending arms of each lever engaging with the top and bottom abutments respectively at the corresponding side of the buffer head to force the head inwardly in draft.

60 8. In a combined draft and buffer gear for cars, the combination with a support; of a transversely disposed buffer head movable inwardly on said

support; cushioning means opposing inward movement of said head; a pulling element adapted to be pulled outwardly in draft; lever members pivoted at opposite sides of said pulling element for actuating said buffer head, said lever members including a pair of laterally, inwardly projecting arms, one on each lever member, said arms being spaced vertically and said pulling element being disposed between said arms; and a coupling link connecting said arms to said pulling 10 element.

9. In a combined draft and buffer gear for cars, the combination with a support; of a transversely disposed buffer head movable inwardly on said support; cushioning means opposing inward movement of said head; a yokelike pulling element having bearing seats at opposite sides thereof; and lever members pivoted on said support at opposite sides of said pulling element for actuating said buffer head in draft, said lever members including laterally, inwardly extending arms having their outer ends engaged in said seats to be swung outwardly upon outward movement of said pulling element.

10. In a combined draft and buffer gear for 25 cars, the combination with a support; of spring abutment means on said support; a transversely disposed buffer head; a central pulling element movable outwardly with respect to said support in draft; levers pivoted on said support at opposite sides of said pulling element for transmitting the actuating force from said pulling element to the buffer head; and spring resistance means opposing inward movement of said head including a plurality of spring elements interposed between said head and said spring abutment means, said elements including a plurality of springs disposed between the pivots of said levers, and additional springs disposed outwardly of said pivots.

11. In a combined draft and buffer gear for cars, the combination with a transversely disposed buffer head at the end of the car; of cushioning means opposing inward movement of said head; a pulling element above said buffer head 45 actuated in draft; and lever means pivoted at opposite sides of the mechanism operatively connected to and actuated by said pulling element and engaging said buffer head at opposite sides to force the same inwardly in draft.

12. In a combined draft and buffer gear for cars, the combination with a transversely disposed buffer head at the end of the car; of cushioning means opposing inward movement of said head; a coupling link slidably supported on top 55 of the buffer head; lever means pivoted on a vertical axis and having engagement with the buffer head to force the same inwardly in draft, said lever means including arms swingable in horizontal planes; and a coupling pin connecting said arms to said link.

STACY B. HASELTINE.
